DESIGN FOR A CHAIR

Roy H. Ziem, Los Angeles, Calif.

Application April 8, 1936, Serial No. 62,002

Term of patent 3½ years

To all whom it may concern:

Be it known that I, Roy H. Ziem, a citizen of the United States, residing at Los Angeles, in the county of Los Angeles and State of California, have invented a new, original, and ornamental Design for a Chair, of which the following is a specification, reference being had to the accompanying drawing, forming part thereof.

Fig. 1 is a perspective view of a chair showing my new design.

Fig. 2 is a top plan view of the chair.

I claim:

The ornamental design for a chair as shown and described.

ROY H. ZIEM.
